CORRIE F. RUDOLPH, OF WASHINGTON, DISTRICT OF COLUMBIA

ELECTRON TUBE APPARATUS

Application filed March 8, 1930. Serial No. 434,282.

My invention relates broadly to electron tube apparatus and more particularly to an apparatus for determining the effective life of an electron tube.

One of the objects of my invention is to provide an automatic apparatus for registering the service life of an electron tube in order that the effective life of the tube may be determined.

Another object of my invention is to provide a circuit arrangement for a counter in association with an electric clock by which the life of an electron tube may be accurately determined and the service given by a radio transmitter for any particular time may be registered.

A further object of my invention is to provide a circuit arrangement for an automatic counter in association with an electric clock energized from the cathode circuit of an electron tube for registering the time period over which the tube is effective and indicating the life of the tube.

Other and further objects of my invention reside in the construction of apparatus for registering the time of service of an electron tube as will be more fully understood from the specification hereinafter following by reference to the accompanying drawings, in which:

Figure 1 is a diagrammatic illustration showing the circuit arrangement, an electric clock associated with a counter mechanism and connected in the cathode circuit of an electron tube system; Fig. 2 illustrates the condition of the mechanism immediately after the receipt of an initial impulse; Fig. 3 is a plan view illustrating the arrangement of parts in the electric clock which is associated with the counter mechanism of my invention; Fig. 4 is a front elevation of the counter mechanism of my invention partially broken away to show the actuating mechanism which is associated therewith; Fig. 5 is a plan view of the counter mechanism with the casing of the counter mechanism broken away to show the operation of the parts therein; Fig. 6 is a cross-sectional view through the magnetic control device for the counter taken on line 6-6 of Fig. 5; and Fig.

7 is a view showing the modified circuit arrangement for the electric clock circuit and the counter mechanism.

In high power transmitters employing electron tubes of large size I have found that for the economic operation and maintenance of the transmitter, it is important to know the relative effective life of the high power tubes which are employed in the transmitter. It is not practical however to install a watt hour meter in the transmitter as this apparatus occupies more space than is available in the modern electron tube transmitter and unreasonably adds to the expense of the apparatus. I have devised a circuit arrangement for a vacuum tube life meter in which a counter mechanism has an actuating winding connected in circuit with the control circuit of an electric clock and is energized in accordance with the impulses received from said electric clock mechanism. I so coordinate an electric counter with the control circuit of the winding mechanism in an electric clock that each impulse derived from the clock mechanism operates to step the counter forward thereby registering the received impulse. The impulses received from the electric clock are transmitted each minute and the counter is provided with sixty ratchet teeth which may be moved by the step by step mechanism in the counter upon receipt of each impulse from the electric clock so that one numeral is shifted on the counter each hour. The reading on the counter therefore directly indicates the number of hours over which the electron has been in use. When the filament of an electron tube burns out the life of the vacuum tube in hours is directly read from the counter. The counter of my invention is a tachometer especially designed for sixty step by step movements for each revolution to effect one complete revolution per hour. Manufacturer's guarantee a certain minimum number of hours life for each vacuum tube and unless an accurate form of counter mechanism is installed in the transmitter the customer has no means of knowing accurately whether or not the tube which has been purchased has actually met the manufacturer's guarantee. With the apparatus

of my invention installed in the transmitter an accurate check on the tube performance is maintained.

Referring to the drawings in detail, reference character 1 indicates an electric clock associated with the counter mechanism indicated at 3. The electromagnetic driving coil 4 of the electric clock is connected in parallel with the driving coil 5 of the counter mechanism. These coils are in turn connected to the contacts 6 of the electric clock and to the filament circuit of vacuum tube 7. The filament circuit of the vacuum tube may be connected to an alternating current source as shown at 8 by the use of the transformer 9 or this circuit may be a direct current circuit. The electric clock is so constructed that the coil 4 energizes the magnetic circuit 10 which in turn actuates armature 11 against the tension of spring 12. Armature 11 gives link mechanism 13 an impulse which stretches spring 25. This spring tension revolves the mechanism of the clock through pawl 14 and ratchet wheel 15. Armature 11 also actuates contacts 6 through arm 16 which is pivoted at 16a. Spring 16b tends to normally hold arm 16 in such position that contacts 6 are closed subject to the opening thereof upon the momentary shifting of the lever 16. In operation the clock is wound up for a given time interval such as one minute by an impulse given by armature 11. The circuit is made through contact 6 for just an instant. Since the coils 4 and 5 are in parallel, whenever coil 4 is energized coil 5 together with its magnetic circuit is also energized.

Figs. 4, 5 and 6 show details of the counter mechanism illustrated in Fig. 1. The magnetic circuit of the counter mechanism includes an armature 17 mounted on bearing 18. A spring 19 brings the armature back to its non-energized position. A combination spring and pawl 20 is mounted on armature 17. This actuates ratchet wheel 21 mounted on a shaft of the counter mechanism 22. This counter mechanism 22 is shown more clearly in Figs. 4 and 5. A stopping spring 23 is provided to prevent the backing up of ratchet wheel 21. The counter mechanism 22 is mounted on a frame 24 which also supports the actuating magnetic system. The number of teeth in the ratchet wheel 21 together with the gear ratchet of counter mechanism 22 are adjusted so that with the time interval of the electric clock 1 when set at a given value the dial of the counter mechanism 22 will read in units of time. These units are normally hours so that a reference to the dial will indicate the total number of hours that a vacuum tube has been in service. The counter mechanism 22 may be provided with a reset device so that it may be reset to zero when a new tube is put in the radio transmitter or the reset device may be left out and the dial reading noted when the

tube is put in place and taken out. In the latter case, subtracting the reading of the dial when the tube is put in place from that when the tube is taken out will give the life of the tube.

In Fig. 2 I have indicated the condition where the electron tube cathode circuit has been energized and an initial impulse has been imparted to the armature of the electromagnetic system in the electric clock producing a winding operation and opening the circuit to the electromagnets 4 and 5. The coils of the counter mechanism of the clock may be arranged in series instead of in parallel. This is shown in Fig. 7 where these coils are connected in series with each other and with contacts 6 of electric clock 1. Whether the parallel connection or the series connection is used depends upon the particular circuit conditions, upon the winding of the coils and the arrangement of associated circuits.

The apparatus of my invention may be inexpensively manufactured and occupies a very small space. The clock may be mounted with respect to the transmitter to provide accurate time when its mechanism is being used in association with the counter mechanism to measure the life of the high power tube used in the transmitter. Another advantage of the system is that the electric clock may be placed at a substantial distance away from the counter mechanism, such as on the front panel of a radio transmitter where it is readily visible, the counter mechanism being located at some remote part of the transmitter and connected to the two conductors illustrated with the electric clock on the front panel. The service life of the radio transmitter for any given interval of time may be measured by the mechanism of my invention as well as the life of the high power tubes used in the apparatus.

While I have described my invention in certain preferred embodiments I desire that it be understood that modifications may be made and that no limitations upon my invention are intended other than are imposed by the scope of the appended claims.

What I claim as new and desire to secure by Letters Patent of the United States is as follows:

1. In a system for measuring the effective life of electron tubes in combination with a cathode circuit of an electron tube, an electric clock, means in said electric clock for producing a characteristically timed succession of impulses, and an electrically driven counter mechanism electrically connected with said means for indicating the total time interval during which the cathode circuit of the electron tube is energized.

2. In a system for measuring the effective number of hours over which an electron tube is operative, the combination with an electron

tube having a cathode circuit of an electric clock energized by power derived from said cathode circuit, means in said electric clock for producing a characteristically timed succession of impulses, and an electrically driven counter mechanism electrically actuated by the characteristically timed succession of impulses from said electric clock for indicating the total number of hours over which the cathode of the electron tube is energized.

3. In a system for registering the service time of an electron tube, the combination of an electron tube having a cathode circuit, means electrically energized from said cathode circuit for producing a characteristically timed succession of impulses, and means electrically operated by the impulses thus produced for registering the time interval over which the cathode circuit of the electron tube is energized.

4. In a system for registering the time interval over which a power consuming circuit is energized, means for producing from said power circuit a characteristically timed succession of impulses, a counter mechanism electrically energized by said impulses, and means energized by said impulses for integrating the total number of such impulses generated for indicating the time period over which said power consuming circuit is energized.

5. In a system for registering the total period of time over which a power consuming circuit is energized, an electric clock connected with said power consuming circuit, said electric clock including means for producing a characteristically timed succession of impulses, and an electrically actuated counter mechanism electrically operated by said electric clock for recording the total time period over which said power consuming circuit is energized.

6. In an electron tube system, an electron tube including a cathode circuit, means for energizing said cathode circuit, an electric clock driven from said cathode circuit, said electric clock including means for producing a characteristically timed succession of impulses, and an electrically actuated counter device electrically driven by the timed succession of impulses produced by said electric clock integrating the total period of time over which said cathode circuit is energized.

7. In a system for measuring the service time of electrical apparatus, the combination of a power supply circuit, an electric clock driven from said power supply circuit, said electric clock having means for producing a characteristically timed succession of electric impulses, and an electrically actuated counter mechanism including magnetic means actuated by said electric impulses for integrating the impulses produced by said clock and registering the total time period over which said power supply circuit is energized.

8. In a system for registering the effective number of service hours of an electron tube, an electron tube including a cathode circuit, an electric clock containing a magnetic control and contact device therein, said magnetic control operating to successively close said contact device, a counter mechanism including an electromagnet, said electromagnet being connected in series with said contact device and with said cathode circuit, and mechanical means driven by said electromagnet for integrating the number of impulses supplied to said electromagnet for registering the total time period over which said cathode circuit is energized.

9. In a system for recording the service life of an electron tube, the combination of an electron tube including a cathode circuit, a source of heating energy connected with said cathode circuit, an electric clock including a magnetic control and a contact device, a counter mechanism including an electromagnet, a ratchet mechanism driven by said electromagnet, and a register controlled thereby, said ratchet mechanism being movable in successive steps sixty times per hour for completing a single revolution and moving said register one unit, the magnetic control and contact device in said electric clock operating to transmit an electric impulse from said source to the electromagnet in said counter each minute during the energization time of said cathode circuit, for measuring the time period during which said cathode circuit is energized for registering the service time of the electron tube.

10. In a system for registering the elapsed time of operation of the supply circuit of an electric device, an integrating counter, an electromagnet for driving said counter and an electrically driven clock mechanism adapted to close the connection of its driving means to said supply circuit intermittently at regular intervals, the actuating winding of said electromagnet of said counter being connected to said supply circuit through the connection of said driving means of said clock, whereby said electromagnet receives impulses of electrical energy intermittently at regular intervals corresponding to the intervals when energy is supplied to said clock.
